UNITED STATES PATENT OFFICE.

ALEXANDER CLARKE, OF BROOKLYN, NEW YORK.

FAUCET.

SPECIFICATION forming part of Letters Patent No. 571,065, dated November 10, 1896.

Application filed April 7, 1896. Serial No. 586,562. (No model.)

To all whom it may concern:

Be it known that I, ALEXANDER CLARKE, a citizen of the United States, residing in Brooklyn, Kings county, State of New York, have 5 invented certain new and useful Improvements in Faucets, of which the following is a specification.

This invention relates to certain new and useful improvements in faucets; and it consists, substantially, in such features of construction, arrangement, and combinations of parts as will hereinafter be more particularly described.

The invention has relation to faucets generally, but more particularly to that class or type of faucet employed in connection with flush-tanks for sewers and the like, which are periodically discharged to effect the flushing.

The invention has for its object the prevention of lost motion between the valve of the faucet and the connecting media through which the same is caused to be operated, and also to provide a faucet of this class or type which is exceedingly simple in construction 25 and one which operates at all times with an equal degree of certainty and effectiveness.

A further object of the invention is the provision of an increased leverage upon the valve as the same is operated to leave its seat 30 through the action of the water as it is caused to descend below its normal height within the tank.

These objects, together with others, I attain by means substantially as I have illustrated in the accompanying drawings, and 35 wherein—

Figure 1 is a vertical sectional elevation of an ordinary flush-tank and showing my invention as embodied in connection therewith, the full lines indicating the normal position of the valve and its float or operating connections and the dotted lines indicating the position assumed by the parts when the height of the water in the tank is lowered by 40 causing a quantity of the water to be discharged from the tank for flushing purposes. Fig. 2 is an enlarged sectional view of the faucet and indicating the construction and arrangement of parts more clearly, the valve 45 being shown in its closed position; and Fig. 3 is a similar view representing the parts in the position which they assume when the

valve is opened. Fig. 4 is a view looking at the faucet from the left. Fig. 5 is an enlarged vertical sectional view of a modification of my improved faucet wherein the valve is operated by an ordinary turning-plug, the said figure indicating in full lines the valve in its closed position, the dotted lines representing the open position thereof. 60

While my invention is capable of a great many different embodiments, I have found such forms thereof as I have herein represented to be exceedingly simple and effective for my purpose, and therefore I have selected 65 the same as the most convenient means for illustration. As before stated, my invention relates mainly to a faucet, whatever the particular use or connection for which the same is employed, and I may either use or adapt my 70 invention to those purposes wherein it is desirable that the same shall be operated automatically, as in the instance of flush-tanks generally, or else I may readily adapt my invention to those uses or purposes wherein the 75 valve of the faucet is opened directly through the medium of a hand operating or turning plug or similar operating devices, such, for instance, as a push pin or plug normally held in its outward or retracted position by means 80 of a spring or any well-known equivalent thereof.

In the practice of the invention it is of course desirable to employ as simple a construction as possible, whether the valve be 85 hand operated or automatically operated, and in connection with both of these forms, as herein shown and to be described, it will be seen that the parts are exceedingly simple and that their effectiveness is sure. 90

In the use of my improved faucet in connection with ordinary flush-tanks it is of course necessary to support the device or contrivance at the required height or position relative to the top of the tank, and for this 95 purpose I have employed certain devices which will be described, and in like manner all the main or essential characteristics of my invention will also be hereinafter described; but it is to be understood that I am not limited to the precise details of construction and arrangement, which, as before stated, have only been herein selected for the purposes of 100 illustration.

Referring to the accompanying drawings, the letter A represents an ordinary "ball-cock," as it is termed, and which, as is well known, incloses the valve of the faucet, as well also as all or the greater part at least of the devices or mechanism by which said valve is operated to be lifted from and again carried to its seat. This said ball-cock, while it might be constructed in a great many different ways, is preferably herein constituted of a tubular portion a, formed with an outer screw-thread b for a suitable distance from its upper end and having at its upper end an annular flange c, leaving an offset opening d, which constitutes the valve-port opening, and the upper surface of the said annular flange forming in this instance the seat of the valve which closes the said valve-opening d. In connection with this described tubular portion of the ball-cock I may employ any suitable form of rising-and-falling valve, and in some instances it would be convenient to employ an ordinary flat valve ground to its seat in the well-known way; but with such form the lifting power required to move the valve from its seat would be much greater than is desirable in practice, and for such reason I prefer the employment of a tilting valve, such, for instance, as I have herein shown. Thus e represents the valve, which is preferably conical in form and of sufficient height or thickness to furnish weight enough to hold the valve to its seat simply by the weight of the column of water above it without any head or pressure being on. In order to furnish the desired tilting movement to the valve, as well as to provide a packing between the valve and its seat, I preferably form an annular groove at the base of the valve and fit upon the lower projecting end f a strip of leather or other suitable material g, and which strip of flexible material is secured by means of a rivet or screw h to the seat of the valve at i. The valve being normally held to its closed position, it is evident that upon the application of a force thereto to open the same it will be carried upwardly or caused to swing in an obvious manner. From this construction and arrangement it is evident that an increased leverage upon the valve is obtained, and whether the same be operated by hand or by automatic devices controlled by the descent and rise of water in the flush-tank the action is the same, and in the case of the flush-tank a comparatively low pressure is required to close the valve to restore it to its normal position.

When used in connection with flush-tanks, some suitable form of float is required, together with suitable intermediate mechanism for controlling and operating the valve in accordance with the rising and falling of the float, and, while various forms of these devices or mechanism could be resorted to, as a convenient and reliable means I prefer to use such, for instance, as I have herein represented, and which will now be described.

Entering the valve at the under side and preferably by being screwed therein is the upper end of the valve-stem m, and this stem instead of being straight throughout its length is only straight for about one-half its length after leaving the valve, and it is then given a slight bend or curve at n and is widened for a suitable distance from its lower end at o, and formed in this widened portion is an elongated slot or notch o', the sides of which constitute guides for a movable roller r, carried on a pin s, loosely held or supported between the bifurcated end of a pivoted or swinging lever s', having its fulcrum upon a small rod or pin t, having its bearings in lugs u, projecting from the side of the tubular portion a of the ball-cock hereinbefore referred to, the side of the tubular portion being cut out at v to accommodate the said lever and permit of the necessary vibrating or swinging action thereof caused by the rise and fall of the float. As before stated, these devices may be varied in their general construction and arrangement, and I am not limited thereto in their precise detail; but inasmuch as I have found in actual practice that they fully subserve their intended functions I prefer to adopt the same. With this particular embodiment of my invention some suitable form of float and connecting means are to be used, and, while these in like manner may be constructed in various ways, I prefer to use such as I have shown and which I will now describe. I take an ordinary hollow glass or metal float and render the same air-tight at its mouth z by the insertion therein of any suitable form of bushing or packing, the said float being indicated at 1 and the bushing or packing at 2, and passing through the said bushing or packing and entering the float is a connecting-rod 3, preferably of a length to reach all the way to the bottom of the float at one end and leaving a sufficient portion projecting from the neck of the float for enabling the proper connection to be made between the said connecting-rod and the pivoted or swinging lever s', hereinbefore referred to. The outer projecting end of the said projecting rod may be joined to the upper or shorter arm of the said lever in any suitable way; but as a convenient way I have formed on the end of the connecting-rod a short screw-threaded portion 120 5, which enters a screw-threaded opening 6, leading into the said shorter arm of the lever from the outer side or face of the latter. It will thus be seen that when the water in the flush-tank is at its ordinary height or level 125 the position of the parts will be as represented in full lines, Fig. 1, that is to say, the valve will be closed down upon its seat, the swinging lever s' will be in an approximate vertical position, and the connecting-rod and float 130 will be in a substantially horizontal position with the latter riding upon the surface of the water. Upon discharging a portion of the contents of the tank for flushing purposes

the column of water in the tank will of course be lowered, and as the same is gradually lowered the float is carried down with it, and consequently the swinging lever s' is carried within the tubular portion a of the ball cock, and in so moving the lower bifurcated end of said lever describes a sweep in the arc of a circle, and the small roller r , carried by the lower end of said lever, is caused to ride 10 against and upon the farther wall of the notch o' in the widened portion of the stem of the valve, and this causes the stem to move upwardly, carrying with it the valve, and then as soon as the tank begins to fill again the parts will gradually assume their original 15 position, and the valve closed, as before. In virtue of the construction of the bend in the stem of the valve the said stem is caused to move more nearly in a vertical line centrally 20 of the offset opening d than would be the case were the stem perfectly straight throughout, and also by so bending the stem it is carried over to one side of the tubular portion a to effect the proper connection with lever s' . 25 Moreover, the abutment or impingement of the outwardly-curved side of the bent portion of the valve-stem against the opposite inner side of the tubular portion a limits the upward movement of the valve and float, and 30 the parts become locked in this position, with no strain on the valve-hinge, until they are restored, as before, by the refilling of the tank. It thus requires but slight movement of the parts to instantly affect the valve both in 35 opening and closing. In connection with this form or embodiment of my invention I employ as a convenient means for inclosing the valve in a way to render the same readily accessible a coupling-tube 10, screw-threaded 40 to fit the upper screw-thread of the tubular portion a , and also having a screw-threaded nipple 11, receiving a nut 12, within which latter is held a connection 13, leading to any suitable source of supply for the flushing 45 tank. This construction is simple and enables the valve to be reached very easily, and while the same constitutes a minor feature only of the invention it is at the same time preferred.

50 Referring to the modification shown in Fig. 5, it will be seen that substantially the same form of valve is employed, but the same is operated by hand instead of being operated

automatically, as before. In this instance the plug of the faucet is hollow, as represented at 15, the valve 16 being hinged at 17 in substantially the same way, and being also provided with substantially the same kind of stem 18, the lower curved portion of the latter normally resting against the side of the 55 plug or faucet, and secured to the outer side of said plug or faucet is a screw-threaded bearing 19, having a bushing or plug 20, and passing through the bushing is an operating stem, to the outer end of which is attached a 60 hand-wheel 21, and which stem presses against the stem of the valve, and by pushing in upon the said stem in one direction the valve 65 will be caused to be lifted or raised from its seat, as shown in dotted lines, Fig. 5, whereas 70 on turning or retracting the stem the said valve will be closed by the force of the head or pressure of water in the supply-pipe. In like manner with this modified construction I am not confined to the precise details of construction of parts, since immaterial changes could be made therein without departing from the scope intended to be embraced. So, therefore, without limiting myself in these particulars,

I claim—

The combination in a faucet, of a tubular portion having a vertical opening in one side thereof, and constructed at its upper end with a valve-seat formed with a port eccentric to the axis of said tubular portion, a hinged valve closing down on said seat and having a valve-stem bent or curved to one side in a part of its length, and notched vertically at its lower end, a swinging bifurcated 85 lever working through the opening in the side of the tubular portion and supported in lugs projecting from the latter, a movable sliding connection between the lower end of the lever and the notched end of the valve-stem, and a 90 float having a rod connecting with the upper end of said swinging lever, substantially as 95 shown and described.

In testimony whereof I have signed my name to this specification in the presence of 100 two subscribing witnesses.

ALEXANDER CLARKE.
